UNITED STATES PATENT OFFICE.

FREDERICK F. CLARKE, OF FRANKLIN, PENNSYLVANIA, ASSIGNOR TO COLBURN MACHINE TOOL COMPANY, OF FRANKLIN, PENNSYLVANIA, A CORPORATION OF PENNSYLVANIA.

FEED-GEAR FOR BORING-MILLS.

1,185,063.

Specification of Letters Patent. Patented May 30, 1916.

Application filed December 3, 1914. Serial No. 875,330.

To all whom it may concern:

Be it known that I, FREDERICK F. CLARKE, citizen of the United States, residing at Franklin, in the county of Venango and 5 State of Pennsylvania, have invented certain new and useful Improvements in Feed-Gears for Boring-Mills, of which the following is a specification.

The object, construction, operation and 10 utility of my improved feed-gear are herein set forth with sufficient clearness to enable those skilled in the art of boring-mill construction to make and use the same.

The gear here shown is especially adapted 15 to be applied to a vertical boring and turning-mill, which is supplied with a side-head, in addition to a vertical head, and the object of the construction here shown is, to supply feed-gearing in which one main or 20 primary element serves the double purpose of driving the train of gearing which causes the feed of both of said heads, and in order to make said object more clear, it is pointed out that, heretofore, what is above termed 25 the "primary" element, has been supplied in duplicate,—that is, the feed-gear for each head has been separately supplied with said element, whereas, in the gearing here shown, said two trains of feed-gearing are driven 30 from the one primary element, which is adapted to perform all of the functions of two such elements, as heretofore employed, thus simplifying the construction and operation of the machine, decreasing the space 35 occupied and the cost of maintenance, and facilitating lubrication, inspection and repair of the machine, without in any respect lessening its power, capacity, utility or range of operation.

40 The construction whereby I attain said object is clearly shown in the drawing which forms a part hereof, and in which:

Figure 1 is an elevation of said gearing, Fig. 2 is a front elevation of a boring mill 45 equipped with my improved feed gears.

Inasmuch as it is necessary to construct gearing which is employed for the purpose here specified, so that the rate of feed may be varied to suit different kinds of work, the 50 drawing shows gearing embodying such construction, and in order to make the same more easily understood, a definite line of drive is indicated through each train of gearing by shading the gears which are in 55 operative action, with the exception that all

the gears upon said primary element are shaded, because they are all keyed to the shaft and are thus positively driven. All unshaded gears may be considered as idle gears which may be selectively engaged and rendered operative for the purpose of changing or varying the rate of speed as desired. 60

In detail, the construction here shown is as follows: I provide a primary driving-element comprising a shaft 1, to which are 65 keyed a number of gears 2, which, being keyed to said shaft 1, are all positively driven. Upon either side of said primary element, is mounted a separate secondary train of gearing, one to drive the side-head 70 of the machine and the other to drive the vertical head. Said secondary trains are practically identical in construction, and, for this reason, reference numerals in duplicate will be applied thereto, since the description of one train is equally applicable 75 to the other. Said secondary train comprises a shaft 3 upon which are revolvably but engageably mounted the gears 4, which are selectively engageable and rendered operative by a key—(not shown)—within said shaft 3, which key is attached to the rack 5; a pinion 6 is operable to move said rack longitudinally, for the purpose of causing 80 said key which is carried thereby to operatively connect any one of said gears 4 to the shaft 3; upon said shaft 3 are also mounted the gears 7, 8 and 9, through which a variable speed-drive may be had through the gears 10, 11 and 12, to the shaft 13. From 85 said shaft 13 motion is transmitted to shaft 14 through the gears 15, 16 and 17. Said shaft 13 is provided with a selective key, for the purpose of operatively engaging any of the gears thereon, which key is operated by 90 the rack 18, which is actuated by the pinion 19.

Shaft 14 is provided with a bevel gear 20 which meshes with and drives the gear 21, which is keyed to the vertical shaft 22, upon 100 which is mounted the clutch-gearing for machine tools, fully shown and described in my pending application, Serial No. 875,331. One of said shafts 22 is arranged 105 to operate said clutch-gearing of the side-head which is contained in the gear housing 22^s, and the other is arranged to operate said clutch-gearing of the vertical head which is contained in the gear housing 22^v. Said clutch-gearing consists of a miter-gear 110

23, which is connected to the shaft 24 to which is rigidly affixed a worm 36 that meshes with and drives the worm gear 37 which operates a pinion 38 that is mounted 5 in the carriage 39 of the side head, and which pinion 38 meshes with the rack 40 upon the frame of the mill, to cause the vertical travel of said side-head carriage and the ram 41 that is mounted therein.

10 In order to simplify the drawings, and to more clearly illustrate the construction, the housing 22^s is shown turned upon the shaft 22 at an angle of 90 degrees from its normal position; in the actual construction, 15 shafts 24 and 26 are in parallel alinement with shafts 24' and 26', as will be seen from an inspection of Fig. 2. Meshing with the gear 23 are two diametrically-positioned gears 27 and 28, which are revolvably mounted upon the clutch-body 29; said gears 27 and 28 are selectively, operatively engageable by said clutch, so that said gear 23 may be driven in either direction. Gears 30 and 31 are likewise mounted upon a clutch- 25 body 32, and co-operate in like manner relative to the gear 25. Said gear 25 is rigidly mounted upon a shaft 26 which carries a worm 42 that meshes with and operates the worm-wheel 43, the shaft 44 and the pinion 30 45; said pinion 45 engages a rack upon the rear side of said ram 41 and thus causes the longitudinal, feed movement of said ram. The clutch-gearing in the housing 22^v is identical with that in the housing 22^s, 35 but to each shaft 24' and 26' is rigidly secured a bevel gear 46 and 47 respectively; gear 46 meshes with a gear 48 which is mounted upon and revolves the screw 50 that causes the travel of the carriage 51 40 upon the cross-rail 52; gear 47 meshes with a gear 49 that is mounted upon and revolves the shaft 53 for the purpose of causing the vertical movement of the vertical head 54. The gears 2 may be driven in any

suitable manner, and in actual practice, I 45 find it suitable to drive the shaft 1 upon which said gears 4 are mounted, by means of a pulley 33, to which power may be transmitted from any suitable source, by means of a belt. It is immaterial, however, 50 so far as my inventive idea is concerned, how gears 4 are driven. It is also immaterial to the suitable embodiment of my invention, whether the two heads, actuated by the gearing here shown, are a side-head 55 and a vertical head, or whether they are two vertical heads.

I claim:

1. In a boring-mill a vertical head, a side head, a train of secondary gearing operable 60 to produce the feed-actuation of one of said heads, an additional train of secondary gearing operable to produce the feed-actuation of the other of said heads, in combination with a single primary element, 65 consisting of gearing arranged to drive both of said secondary trains.

2. In a feed gear for a boring mill a vertical head, a side head, a primary, or main driving gear consisting of a plurality of 70 spur gears of differing diameters rigidly mounted upon a shaft which is operable to drive said gears, in combination with a train of gearing adapted to be variably driven by said primary gear and arranged 75 to transmit and impart feed motion to said vertical head, and a second train of gearing substantially identical in construction with said first-mentioned train of gearing, adapted to be variably driven by said primary 80 gear and to transmit and impart feed motion to said side head.

In testimony whereof I affix my signature in presence of two witnesses.

FREDERICK F. CLARKE.

Witnesses:
